RIDER STEERED POWER LAWN MOWER

Robert J. McKnight, Springfield, Ohio, assignor to
Orly Musgrave, Springfield, Ohio

Application October 18, 1956, Serial No. 43,407

Term of patent 14 years

(Cl. D40—1)

Figure 1 is a perspective view of a rider steered power lawn mower embodying my new design;

Figure 2 is a left side elevational view thereof;

Figure 3 is a right side elevational view thereof;

Figure 4 is a front elevational view thereof;

Figure 5 is a rear elevational view; and

Figure 6 is a top plan view of the design of Figure 1.

I claim:

The ornamental design for a rider steered power lawn mower, substantially as shown.
